UNITED STATES PATENT OFFICE.

MICHAEL E. SULLIVAN, OF NEW BEDFORD, AND GEORGE O. DRAPER, OF HOPEDALE, MASSACHUSETTS, ASSIGNEES TO THE DRAPER COMPANY, OF PORTLAND, MAINE, AND HOPEDALE, MASSACHUSETTS.

YARN SPINNING OR TWISTING APPARATUS.

SPECIFICATION forming part of Letters Patent No. 660,668, dated October 30, 1900.

Application filed May 9, 1900. Serial No. 16,043. (No model.)

To all whom it may concern:

Be it known that we, MICHAEL E. SULLIVAN, of New Bedford, county of Bristol, and GEORGE O. DRAPER, of Hopedale, county of Worcester, State of Massachusetts, have invented an Improvement in Yarn Spinning or Twisting Apparatus, of which the following description, in connection with the accompanying drawings, is a specification, like figures on the drawings representing like parts.

This invention relates to yarn spinning or twisting apparatus, and more particularly to forms of such apparatus wherein high spindle speed is attained—such, for instance, as from ten to fifteen thousand revolutions per minute—it being manifest that, other things being equal, increased production per frame is the result of increased spindle speed.

In a recent type of spinning or twisting apparatus the annular traveler support or ring is arranged to rotate freely when the spindle is in motion, and when so rotating the ring is free to yield in any direction under unbalanced strains, the rotation of the ring obviating the destructive heating of the traveler by friction against the ring. The traveler used in such apparatus has, as usual, two bearing-points on the rotatable ring; but in practice certain objectionable features have developed, one of which is the difficulty of at times controlling the momentum of the ring, due to the very rapid rotation of the ring, such difficulty being particularly noticeable when stopping the frame. It has also been found necessary to provide elaborate means for cushioning or yieldingly controlling the lateral or radial movements of the ring.

Our present invention has among other objects the production of means for obviating the objectionable features hereinabove referred to; and in the practical embodiment of our invention we utilize the usual principle of a traveler with two bearing-points; but we have provided fixed and movable races or supporting-surfaces for the bearing portions of the traveler, whereby the friction of the latter is governed by engagement with the fixed race or surface, while still permitting

the traveler to carry or rotatively move the other race or supporting-surface with it. 50

It is well known to those skilled in spinning or twisting apparatus that a traveler by or through centrifugal action bears harder on the inner flange of the ring, and in the preferred form of our present invention the inner supporting surface or race is permitted to rotate with the traveler, thus diminishing the frictional resistance, while the outer engaging portion of the traveler bears on or travels upon the outer fixed race. 55 60

We have herein shown our novel duplex "traveler-support," as it may be termed, so constructed that it will fit the usual ring-holder, so that old or common rings of well-known construction may be replaced by our 65 improved traveler-support without necessitating further change of the parts.

Referring now to the drawings, which illustrate a practical embodiment of our invention, Figure 1, in elevation and partly in section, represents the spindle-rail, spindle and bobbin, ring-rail, and one form of our novel traveler-support or ring on the line xx , Fig. 2, the spindle and bobbin being broken off to save space. Fig. 2 is a top or plan view of the 75 parts shown in Fig. 1, the spindle and bobbin being omitted. Fig. 3 is an enlarged section detail on the line xx , Fig. 1. Fig. 4 is a part elevation and section of a modified form of our invention on the line yy , Fig. 5; and Fig. 80 5 is a top or plan view of the traveler-support and traveler shown in Fig. 4.

Our invention is not restricted to use in connection with any particular type of spinning or twisting frame, and herein the spindle-rail 2, reciprocating ring-rail 3, spindle 4 of any suitable high-speed type, provided with a whirl 5 for the driving band or belt 6, actuated by usual driving means, (not shown,) the removable bobbin 7, on which the yarn is 85 wound, and the circular aperture 8 in the ring-rail, through which the spindle and bobbin extend, may be and are all of well-known or usual construction in spinning or twisting apparatus, it being understood that each ring-rail has a plurality of the apertures 8 corre- 90 95

sponding to the number of spindles. We have also shown a well-known form of ring-holder, comprising a sheet-metal annular base 12, radially notched at its periphery at 13 to 5 receive the shanks of headed screws 14, which secure the holder to the ring-rail, struck-up or bent lugs or ears 15 on the base serving to hold the traveler-support or ring in place, it being understood that the inner circumferential portion 16 of the base extends inward somewhat beyond said retaining-lugs.

Referring now more particularly to Figs. 1, 2, and 3, our novel traveler-support is shown as comprising inner and outer concentric 15 and relatively-movable members or rings 20, 30, separated by a sufficient space or clearance 19, Fig. 3, to permit free but limited radial movement of the inner member 20, which latter is provided at its upper end with an in-turned circular flange 21, which constitutes a traveler-race or supporting-surface, the foot of the said member being shown as thickened or enlarged in cross-section to provide additional weight for steadyng its movement, 20 and herein the foot is shown as provided with an external annular projection or rib 22. The part 16 of the holder 12 projects beneath the foot of the inner member 20 and supports the same when at rest. The outer member 30 25 has at its upper end an outwardly-extended circular flange 31, which retains the traveler in place and at times forms a race therefor, the main race, however, being formed by the upright outer face 33 of the member 30, the 30 widened foot 34 of said member (see Figs. 1 and 3) being engaged and held stationary by frictional contact with the lugs 15 of the holder, while the inner side of the foot has an annular overhanging shoulder 32, beneath 35 which the rib or projection 22 of the rotatable member 20 freely extends, the clearance between the rib-shoulder permitting axial or up-and-down movement of the member 20.

The traveler 40, of well-known form, has 40 its ends 41, 42 extended inwardly, and it is adapted to travel on the races formed on the fixed and movable members of the duplex ring or traveler-support described.

The yarn passes from the usual delivery- 50 rolls and pigtail orguide (not shown) through the traveler to the bobbin, and when the spindle and bobbin are rotated at high speed the pull of the yarn causes the traveler to revolve about the double race, at such time the traveler, by its friction on the rotatable ring, 55 causing it to rotate with increasing rapidity until to all appearances the traveler and ring move in unison. At the same time the tension of the yarn raises the rotating ring from engagement with the foot or projecting part 60 of the holder, undue lift of the ring being prevented by the shoulder 32 of the fixed ring or member 30; and at the same time the traveler is moved by centrifugal force into substantially the position shown in Figs. 1 and 65 3, its end 42 traveling upon the upright bearing-surface 33 of the fixed ring. When the

rotatable member is rotating at full speed, it rarely contacts with the fixed member, seeking to center itself and adjust itself axially 70 in the so-called "rotary ring-spinning apparatus," hereinbefore referred to. So far as we are able to discover, the clearance between the fixed and movable members forms practically an air-cushion which is self-adapting 75 to the requirements of the apparatus. The engagement of the traveler with the fixed and movable members appears also to aid in maintaining the parts in proper concentric position when in operation. The clearance between the fixed and rotatable members of the traveler-support or ring also permits sufficient movement of the rotatable member to counteract the effect of sudden strains.

In the drawings the rotatable member is 80 not shown as lifted by the tension of the yarn in order to more clearly show the clearance between the shoulder 32 and rib 22.

We prefer to make the inner member rotatable; but, if desired, the arrangement may 85 be reversed, as shown in Figs. 4 and 5, wherein the inner member 50 has at its foot an external flange 51, to be engaged and held from rotation by the lugs 15 of the holder, an in-turned flange 52 at the top of the member 90 50 forming the race for the traveler, while the outer member 60, loosely surrounding the inner member, rests on the flange 51 when the apparatus is at rest. The outer rotatable member 60 has at its upper end an outwardly-extended flange 61 to retain the traveler in 95 place when starting up, and as full speed is attained the outer end of the traveler will engage the upright face or race 62 below the flange, the member 60 then being lifted from its support and rotating freely about the fixed member 50.

In Figs. 1 and 4 the clearance between the members of the ring is indicated by a heavy line 19 in Fig. 1 and 65 in Fig. 2.

To assemble the duplex ring shown in Fig. 1, the member 20 is slipped into the outer member 30 and the latter is sprung into the holder, while in the modification shown in Fig. 4 the inner member 50 is sprung into the 115 holder and the outer member 60 dropped into place surrounding the fixed member.

It will be manifest that our duplex ring of either form herein shown can be readily substituted in a frame for rings now in use, utilizing the old holders.

Our invention is not restricted to the precise construction and arrangement herein shown, as the same may be varied or rearranged without departing from the spirit and scope of our invention.

Having fully described our invention, what we claim, and desire to secure by Letters Patent, is—

1. In a spinning or twisting frame, a duplex traveler-support composed of a fixed and a movable member each having a race for the traveler.
2. In a spinning or twisting frame, a du-

- plex traveler-support comprising rotatable and non-rotatable members provided with races for a common traveler.
3. In a spinning or twisting frame, an annular traveler-support comprising a plurality of members one of which is fixed, each member having a bearing surface or race for a common traveler.
4. In a spinning or twisting frame, a traveler-support having a fixed race and a rotatable, radially-movable race for the traveler.
5. A drag for a spinning or twisting frame consisting of fixed and radially-movable rotatable races for a traveler.
- 15 6. A drag for a spinning or twisting frame, consisting of concentric fixed and rotatable annular members each having a race for a traveler.
7. The combination of a rotatable ring capable of radial and vertical movement, a fixed ring, and a traveler coöperating with both rings.
8. The combination of a rotatable ring capable of radial and vertical movement, a fixed ring, oppositely-extended flanges on said rings, and a traveler coöperating with the rings and retained thereon by the flanges.
9. The combination of a rotatable, flanged ring-section with a non-rotatable, flanged and concentric section, and a traveler coöperating with the flanges of both sections.
10. The combination in a duplex spinning-ring, of a stationary flanged section and a movable, flanged section, each providing races for the traveler.
- 35 11. The combination of a rotatable ring capable of axial movement relatively to the spindle under the stress of the yarn, means for limiting the movement of the ring, and a traveler in engagement with said means and with the ring.
12. The combination, with a traveler, of fixed and movable annular bearings therefor.
13. In a spinning and twisting frame, a duplex ring composed of a fixed and a rotatable section, each provided with a bearing-race for the traveler, the movable section being weighted below its race.
14. In a spinning and twisting frame, a fixed outer member having a traveler-race, and a rotatable inner member also provided with a traveler-race.
15. A traveler-support for spinning and twisting frames, consisting of concentric, annular members one of which is rotatably and axially movable relative to the other and each having a traveler-race, and means to limit relative axial movement of said members.
16. In a spinning or twisting frame, a rotatable ring freely movable in any direction under unbalanced strains, a traveler coöperating therewith, and means to retard the rotation of the traveler independently of the ring.
17. The combination with relatively-movable traveler-supports, of a traveler coöperating with each.
18. The combination with relatively-movable traveler-supports, of a traveler coöperating with each, and means to retain the traveler in engagement therewith.
19. In a spinning or twisting frame, an annular traveler-support comprising two relatively-movable members each having a traveler-race, one of said members having a lateral projection to extend beneath an overhanging shoulder on the other member.
20. A drag for a spinning or twisting frame consisting of a rotatable, circularly-flanged member for the traveler, and a coöperating confining member provided with a flange, with which the traveler also coöperates.
21. The combination of a rotatable ring axially and radially movable relatively to the spindle, said ring having a race, a traveler revolvable about the race, and means for limiting the described movement of said ring, said means also having a race for the traveler.
22. In combination, a rotatable ring and a relatively-fixed ring with a space between them to admit of radial movement of the rotatable ring relatively to the fixed ring, and a traveler-race on each ring.
23. The combination of a fixed guide, a rotatable ring capable of radial movement relatively to said guide, and a traveler revolvable about and in engagement with said ring and guide.
24. The combination of fixed and movable annular bearings for a traveler, with a common support or holder.
